REPEATING FUSE CONSTRUCTION

William O. Schultz, South Milwaukee, and Alwin G. Steinmayer, Milwaukee, Wis., assignors to Line Material Company, South Milwaukee, Wis., a corporation of Delaware

P R I O R I T Y

SEP 10 1940

Application June 26, 1933, Serial No. 677,654

14 Claims. (Cl. 200—126)

This invention relates to a repeating fuse construction and is particularly directed to a construction in which a device is provided which closes the circuit after the blowing of a fuse and 5 connects a fresh or reserve fuse in the circuit, such device being capable of repeating as many times as the device is designed for.

The advantage of this automatic repeating fuse construction is that the device lends itself 10 to transmission service and customer's substation service. Frequently in these services short-circuits occur due to any one of many causes, such as a tree falling across a pair of lines, a pair of lines being whipped together by a wind, 15 a flashover, a temporary ground, or the branch of a tree which in a violent wind may be blown against the line. Under these and similar conditions it frequently happens that the trouble is only temporary and that it either ceases of 20 itself or the fault is burned out almost immediately.

This invention is designed to provide a device 25 which will take care of conditions such as outlined above, which will electrically disconnect the blown fuse from the line, and after a predetermined brief interval immediately connect a reserve or fresh fuse in the line, such device providing for the successive operation of as many 30 fuses as the device is equipped to handle, and to provide a device of this type in which the time delay interval is automatically secured from the inherent characteristics of the device itself without requiring any auxiliary timing mechanism.

35 Also in a device of this type it is obviously desirable to provide for the re-fusing of the blown fuse while the service is still maintained through one of the auxiliary fuses.

This invention provides for the renewal of a 40 blown fuse without interrupting the service, and objects of this invention are to provide a construction which permits the ready removal and re-fusing of the blown fuse, which permits the ready restoring of such re-fused fuse, and the automatic disconnecting of the next adjacent auxiliary or reserve fuse without at any time interrupting the circuit during this restoring operation.

45 One of the primary objects of this invention is to provide a construction in which the fuses are all mechanically in place initially, in which no fuse has to be first mechanically moved into place before it is ready to operate upon the blowing of a preceding or first fuse, in which 50 the auxiliary or reserve fuses, although mechan-

ically in place, are nevertheless automatically electrically connected in service in succession as the preceding fuse or fuses blow.

Further objects are to provide a construction 5 in which the device is eminently adapted for high voltage lines, in which each fuse as it blows drops downwardly and swings clear of the upper contact to thereby provide maximum spacing at the open portion of the circuit, and which nevertheless is rugged in construction, is simple to 10 make, and is simple to install and is very easy to renew.

Further objects are to provide a construction 15 in which the blown fuse or fuses may be readily removed by a switch hook or switch stick and may be readily replaced by such switch stick and again placed in service without requiring handling of any high tension part by the operator.

Further objects are to provide an automatic 20 device in which the free falling of the blown fuse automatically closes a switch to establish a circuit through the next reserve fuse, which locks the switch in closed position, in which the falling cartridge may be removed and the continuity of 25 service maintained, in which the re-fused cartridge when rocked to closed position automatically restores itself, that is to say, restores the service through the first fuse, unlocking the switch and disconnecting the next reserve fuse, the restored fuse, however, establishing its own 30 circuit prior to the interruption of the circuit through the next adjacent reserve fuse.

In general, this invention has the same objects 35 for each individual fuse structure as those disclosed in our copending application Serial No. 622,292 for Combined switch and fuse, filed July 13, 1932.

An embodiment of the invention is shown in the accompanying drawings, in which:

Figure 1 is an elevation of the structure.

Figure 2 is a sectional view on the line 2—2 of 40 Figure 1, with parts broken away, with the element 22 of the right hand fuse unit, as viewed in Figure 1, omitted for the sake of clearness.

Figure 3 is an enlarged sectional view on the 45 line 3—3 of Figure 1.

Figure 4 is a fragmentary detail of the lower portion of one of the fuses, such fuse being removed from the remainder of the structure.

Referring to the drawings, it will be seen that 50 the fuse is carried by a base of any suitable type, such, for example, as the frame metal base, which may consist of upright channel or angle members 1, and upper and lower angle or channel members 2 and 3.

A plurality of upper insulators 4 extend outwardly from the upper member 2 and a plurality of lower insulators 5 extend outwardly from the lower member 3, though it is to be distinctly understood that any suitable arrangement of base and insulator supports can be used without departing from the spirit of the invention. For instance, it is obvious that either a single insulator, two insulators, or any number of insulators could be used to support the bar 6, hereinafter described.

The upper insulators 4 carry a transversely extending connecting bar 6 to which a plurality of upper contact members 7 are secured. These upper contact members 7 are all connected and each is preferably provided with a latch-like sleet hood 8, as described in our copending application. Preferably each of the contacts 7 is provided with an upper copper or bronze brush 9 which resiliently bears against the flat face of the upper contact 10 of the fuse 11. This sleet hood or locking member may be released by pulling downwardly upon the switch hook ring or operating member 12, such member being provided with a forked rear portion equipped with arms 13 which are located below the latching member 8 and serve to raise the latching member, thereby permitting the upper end or pin 14 of the upper contact 10 of the fuse to clear the latching member and thus permitting the opening of the device if it is desired to manually open it. This specific construction, however, is described in great detail in our copending application.

One of the upper contacts 7 is provided with a lead in terminal 15. Each of the lower insulators 5 carries a supporting bracket 16 to which is bolted a member 17 provided with a lower hook-like bottom support 18. A terminal carrying bracket 19 is bolted below the member 17, see Figure 3, and is provided with a lead receiving terminal 20.

For each of the succeeding fuses a contact bracket 21 replaces the bracket 19 and each of these contact brackets is provided with a contact arm 22 projecting laterally towards the next adjacent fuse, see Figures 1 and 2. The bracket 19 and each of the brackets 21 is provided with spring contact brushes, such as copper or bronze brushes, as indicated by the reference character 23, see Figure 3. These brushes bear against a normally substantially vertical lever 24, see Figure 2, which is pivoted at 25 upon an intermediate member 26 carried by the fuse tube adjacent its lower end. Each of the levers 24 is provided with outwardly projecting trunnions 27 which are removably received within the hook supports 18. Further, each of these levers 24 is provided with outwardly projecting intermediate pins 28 which carry rubber bumpers or stops 29 for a purpose hereinafter to appear. This construction is most clearly shown in Figures 2 and 3.

From Figure 4 it will be seen that the fuse link which extends downwardly from the upper contact has its leader passing through the lower end of the fuse tube 11 and is clamped to the lever 24 by means of a nut 30 carried by a threaded stud 31' which latter is integral or rigid with the lever 24. The slight turning motion of the nut while turning it in place, serves to draw the link taut as the link is wrapped around the stud. However, when the fuse link blows, the lever 24 allows the fuse tube to swing outwardly and drop downwardly, thus allowing the upper pin 14 of the upper contact, see Figure 2, to clear the latch 24 or sleet hood 8, as described in greater detail in

our copending application. The fuse tube then swings outwardly into the position shown in Figure 3.

A rocking bracket or frame is pivotally carried by each of the lower terminal members or contact members 17, as shown in Figure 3, and is pivoted thereto as indicated by the reference character 31. This frame consists of a pair of spaced arms 32 located on opposite sides of the fuse tube and adapted to be struck by the bumpers 29 when the fuse swings to its lowermost position, as shown in Figure 3. The upper end of this rocking frame is provided with a transverse portion 33 which is located below the face 34 of a spring pressed latch 35. However, when the rocking frame is rocked outwardly into the position shown in Figure 3, the transverse portion 33 bears against a shoulder 36 formed on the latch 35 and thus locks the frame in the position shown in Figure 3.

The rocking frame is provided with an outwardly projecting arm 37, see Figure 1, which carries spring contact brushes 38 which form a switch member and which when the frame is in the position shown in Figure 3, engages the underside of the member 22 and thus electrically connects the lower contact of the next adjacent fuse with the lower contact of the blown fuse. This construction is repeated for the intermediate fuse so that when the intermediate fuse 11' blows, the outer fuse 11'' will then be electrically connected in circuit. Obviously as many of these fuse units can be employed as desired. The end fuse 11'' need not be provided with the outwardly projecting arm 37 on its rocking frame 32.

It is to be noted that the rocking frame 32 is urged inwardly by means of the spring 39, see Figure 3, so that the transverse portion 33 is firmly held on the shoulder 36 of the spring pressed latch 35. When the parts are locked in this position, the switch arm or contact brushes 38 are held in firm engagement with the contact plate 22 of the next adjacent fuse when the first fuse has blown, as shown in Figures 1 and 3.

It is preferable to provide a flexible connector as indicated by the reference character 40, see Figure 2, which joins the switch arm or contact brush 38 with the bracket 21 or with some other portion connected with the lower terminal of its fuse unit. Also it is preferable to provide an arcing contact 38', see Figure 2, for the spring brushes or switch arm 38.

It is to be noted that the member 26 is provided with a rearwardly projecting face portion 41 which engages the upwardly projecting finger 42 of the spring pressed latch 35 so as to release the latch when the blown fuse, after having been re-fused, is rocked into operative position, as shown in Figure 2, or as shown in the last two fuses of Figure 1.

Further, it is preferable to provide the member 26 with an outwardly projecting arm 43 which is adapted to be engaged by a switch stick so that the fuse may be bodily lifted by the switch stick from the lower hook-shaped members 18 and may be replaced and thereafter rocked into position by means of the switch stick through the medium of the upper ring 12, for instance.

In the operation of the device it will be seen that all of the fuses are mechanically in place. If an overload occurs, the first fuse will blow and the fuse tube 11 will first drop downwardly, due to the rocking motion of the then released lever 24, and thereafter rock outwardly and downwardly to its final bottom position, as shown in

the left hand side of Figure 1 and in Figure 3.

Until the fuse has completed its rocking motion, the remaining fuses are electrically out of circuit, though mechanically in position. As the fuse completes its downward swing, the bumpers 29 or the pins 28, if the bumpers are omitted, engage the forked arms of the frame 32 and rock this frame into the position shown in Figure 3, the latch 35 snapping into place. As the frame 32 is rocked quickly into the position shown in Figure 3, which corresponds to the left hand unit of Figure 1, it will be seen that the contact brushes or switch member 38 engages the underside of the contact plate 22 of the next fuse and thus electrically connects the next fuse in the circuit.

If the fault has been cleared, obviously the next fuse does not blow but maintains the service. However, if the fault has not cleared, the next fuse 11' operates as described for the first fuse 11 and successively connects the next fuse 11" in the circuit.

It frequently happens, as stated previously, that the fault is only a temporary one and that after the blowing of one fuse, the fault is gone, as, for instance, when a branch is suddenly violently blown in contact with a line, or when a flashover occurs, or any other of this type of temporary short-circuit condition obtains.

A certain interval is required for the free falling of the fuse and this time delay or interval, which is inherent in the construction of the apparatus itself and not dependent upon any auxiliary timing mechanism, insures a certain predetermined lapse of time before the next successive fuse is electrically connected into the circuit.

Further it is to be noted particularly that after the blown fuse has been re-fused and is being rocked into place, that before the member 26 engages the finger 42 of the spring pressed latch 35, that the upper contact 19 has engaged the extended unflexed contact brush 9. Continued motion of the fuse towards closed position releases the latch 35 and allows the frame 32 to be snapped back or be drawn back by the spring 39, see Figure 3, into its initial position, thereby rocking the switch member or brush 38 from engagement with the plate 22 and opening the circuit through the next or reserve fuse. During a brief instant just prior to the final closing motion of the fuse, it is obvious that two of the fuses temporarily carry the current in parallel and thus no interruption of the service is occasioned during the reclosing of the fuse.

It will be seen that a novel and very rugged form of automatic or repeating fuse mechanism has been provided by this invention which does not require any cocking or setting of the mechanism, which does not require the mechanical throwing or rocking of the fuse into position, but which has the reserve fuses already in their mechanical position and electrically connects in succession the reserve fuses as the next preceding fuse blows.

It will be seen further that no auxiliary timing mechanism is required for this construction but that the construction is wholly automatic both in resetting and opening the circuit through the next adjacent reserve fuse and in establishing this circuit when the preceding fuse blows.

It will be seen further that the construction is very simple, that it is easy to operate, and that it may be operated by means of a switch

stick or fuse stick, thereby guarding against damage to the lineman or operator.

Although this invention has been described in considerable detail, it is to be understood that such description is intended as illustrative rather than limiting, as the invention may be variously embodied and is to be interpreted as claimed.

We claim:

1. A repeating fuse construction comprising a first fuse unit and a second fuse unit, a fuse link in each unit, an electric line normally connected through said first fuse unit, both said units being normally mechanically held in operative position, said first fuse unit being biased towards motion away from its normal position, means for releasing said first fuse unit upon blowing of the fuse link of said first fuse unit, said first fuse unit being movable to inoperative position upon blowing of the link of said first unit, and a switch directly moved by the movement of said first fuse unit for electrically connecting said second fuse unit in said electric line, said switch normally occupying open circuit position and being moved by the movement of the first fuse unit.

2. A repeating fuse construction comprising a first fuse unit and a second fuse unit, a fuse link in each unit, an electric line normally connected through said first fuse unit, both said units being normally mechanically held in operative position, said first fuse unit being biased towards motion away from its normal position, means for releasing said first fuse unit upon blowing of the fuse link of said first fuse unit, said first fuse unit being movable to inoperative position upon blowing of the link of said first unit, and a switch directly moved by the movement of said first fuse unit for electrically connecting said second fuse unit in said electric line after said first fuse unit has moved to a predetermined position, said switch normally occupying open circuit position and being moved by the movement of the first fuse unit, whereby a predetermined time delay is secured between the operation of said first fuse unit and the reclosing of the circuit through said second fuse unit.

3. An automatic repeating fuse construction comprising a first fuse unit and a second fuse unit, an electric line normally connected through said first fuse unit, both said fuse units being normally mechanically held in operative position, means for releasing said first fuse unit upon blowing of said first fuse unit, means actuated by the movement of said first fuse unit for connecting said electrical line through said second fuse unit, and locking means for positively locking said second mentioned means after said first mentioned means has operated, whereby said first fuse unit may be removed for re-fusing without disturbing the circuit through said second fuse unit.

4. An automatic repeating fuse construction comprising a first fuse unit and a second fuse unit, an electric line normally connected through said first fuse unit, both said fuse units being normally mechanically held in operative position, means for releasing said first fuse unit upon blowing of said first fuse unit, means actuated by the movement of said first fuse unit for connecting said electrical line through said second fuse unit, and locking means for locking said second mentioned means after said first mentioned means has operated, said locking means being released by said first fuse unit when said
